UNITED STATES PATENT OFFICE

JACOB C. JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY

MACHINE FOR INSERTING FASTENINGS

Application filed March 27, 1931. Serial No. 525,818.

This invention relates to machines including in their organization means for inserting or driving fastenings, and is herein disclosed as applied to a heel-seat lasting machine of the type illustrated in Letters Patent No. 1,852,015, granted upon an application of mine on April 5, 1932. It is to be understood, however, that the invention is not limited to machines of that particular type nor to machines for lasting shoes.

Machines of the type disclosed in the above-mentioned Letters Patent have an automatically determined cycle of operations to wipe the heel end of the upper into lasted position and to drive a gang of tacks to fasten the upper. It is sometimes desirable to run such a machine through its cycle a plurality of times without any work in the machine, in order, for example, to assist by use of the tack drivers in dislodging some obstruction that may interfere with the closing movement of one or more of the tack-holding fingers. The present invention provides novel controlling mechanism whereby the feeding of tacks may be prevented when the machine is used in this manner, thus avoiding undue waste of tacks. The invention is illustrated as embodied in a modification of controlling mechanism heretofore provided in machines of the above-mentioned type for preventing both the feeding of tacks and the operation of the driving means when it is desired to wipe the upper over the insole a greater number of times than provided for by a single cycle of operations, the construction shown comprising a device movable either into position to prevent the feeding of tacks and the operation of the driving means, as heretofore, or into position to prevent the feeding of tacks without interfering with the operation of the driving means. This enables the operator readily to control the machine in such manner as to produce either of the desired results.

The novel features of the invention will now be more particularly described by reference to the accompanying drawings and thereafter pointed out in the claims.

In the drawings,
50 Fig. 1 is a view partly in right-hand side

elevation and partly in vertical section, showing a portion of the head of a machine in which the invention is embodied;

Fig. 2 is a view of a portion of the head of the machine in left-hand side elevation, 55 showing, as in Fig. 1, the novel controlling mechanism in the position that it occupies when preventing both the operation of the driving means and the feeding of tacks;

Fig. 3 is a detail view showing the controlling mechanism in the position that it occupies when preventing the feeding of tacks without interfering with the operation of the driving means; and

Fig. 4 is a sectional view illustrating more 65 clearly certain details of the controlling mechanism.

Machines of the type illustrated in the above-mentioned Letters Patent include in their organization wipers 10 for wiping the 70 margin of the heel end of an upper over an insole on a last, each wiper having thereon a group of tackers for driving tacks to fasten the upper to the insole. The tackers comprise spring-controlled fingers 12 which 75 operate with flanges 14 on the wipers to provide tack pockets for holding the tacks in position to be driven, and drivers 16 for driving the tacks, the group of drivers associated with each wiper being secured to an 80 operating block or head 18 having a stud 20 mounted in a slot (not shown) in an operating member 22 so that the wipers and the blocks 18 may move in a horizontal plane 85 relatively to the member 22. The member 22 is connected by a link 24 to a vertically movable driver-operating head 26 which is connected by a link 28 to a pivotally mounted lever 30. The lever 30 is controlled by a cam 32 on a power-driven cam shaft 34 by which 90 the wipers and other parts of the machine also are operated, this cam acting on a plunger 36 to lift the lever 30 against the resistance of springs 38. When the cam releases the plunger 36 the springs 38 move the lever 95 30 downwardly to operate the drivers 16 and thus drive the tacks. It will be understood that the wipers and the drivers are operated at automatically determined times in a cycle 100 of operations of the machine corresponding

to a complete revolution of the cam shaft 34 and that the machine comes automatically to a stop at the end of the cycle.

At the proper time in the cycle also tacks 5 are fed to the tack pockets under the drivers 16 through flexible tubes 40 which receive the tacks from a separator 42 movable across the lower ends of a plurality of inclined raceways formed in a raceway block 44. The 10 tacks are supplied to the raceways by an oscillatory tack hopper 46 fast on a rock shaft 48 which is operated yieldingly through a rack bar 50 and a spring 52 by a cam (not shown) on the cam shaft 34. It will be understood that in each cycle of the machine 15 the rock shaft and hopper are moved first in one direction and then in the reverse direction. The separator 42 also is operated by the rock shaft 48 through connections not herein shown in detail but including an inclined rock shaft 54 operated through a universal joint by the shaft 48 and connected by gearing to another shaft 56 which has a yielding connection with a slide 58 on which the separator is mounted. For a more complete 20 understanding of details of the tack-feeding mechanism reference may be made to Letters Patent No. 1,129,881, granted on March 2, 1915 upon application of R. F. 25 McFeely. The tacks are fed to the tack pockets near the end of each cycle, ready to be driven into a shoe operated upon by the machine in the next cycle.

Machines of the illustrated type have been 30 provided heretofore with controlling mechanism whereby both the feeding of tacks and the operation of the driving means may be prevented during the cycle of the machine, so that the upper may, when desired, be wiped inwardly over the insole a greater 35 number of times before it is fastened than provided for by a single cycle of operations. This mechanism comprises a lever 60 fast on a rock shaft 62 mounted on the head of the 40 machine, the upper arm of this lever being movable into position to engage a lug 64 on the tack hopper 46 and thus to prevent the rock shaft 48 from moving far enough, under the influence of the yieldingly operated rack 45 bar 50, to cause the separator 42 to separate tacks from the raceways. The lower arm of the lever 60 has a pin-and-slot connection 50 with a forked slide 66 which is movable into position to embrace the plunger 36 under shoulders 68 on the plunger and thus to prevent such downward movement of the lever 30 as to operate the tack drivers 16 when the upper arm of the lever 60 is in position to prevent the feeding of tacks. For moving 55 the lever 60 into position thus to prevent the feeding of tacks and the operation of the drivers or into position to permit these operations as a part of the normal cycle of the machine, there is fast on the rock shaft 62 a 60 hand lever 70.

In the use of a machine of the illustrated type it may sometimes be desired to run the machine through its cycle a plurality of times without any work in the machine, in order, for example, to assist by use of the tack drivers 16 in dislodging some obstruction that may interfere with the closing movement of one or more of the tack fingers 12. For 70 purposes of the present invention the above-described controlling mechanism is so constructed that in one position, while permitting such operation of the drivers, it will prevent the feeding of tacks, so as to avoid undue waste of tacks as well as annoyances due to the discharge of large numbers of tacks. This position of the mechanism is illustrated in Fig. 3, where it will be observed that the slide 66 is withdrawn from under the shoulders 68, but that the upper arm of the lever 60 is in position to engage the lug 64 on the tack hopper and thus to prevent the feeding of tacks. Alternatively the controlling mechanism may be positioned as illustrated in Figs. 1 and 2 to prevent both the 75 feeding of tacks and the operation of the drivers, as heretofore, or may be moved to a position in which the lever 60 is out of the path of movement of the lug 64 and the slide 66 withdrawn from under the shoulders 68, so that the machine may perform its normal 80 cycle of operations. To maintain the mechanism yieldingly in any of these positions, a rearwardly extending arm 72 of the hand lever 70 carries a spring-controlled plunger 74 arranged to enter any one of three depressions 76 formed in a bracket 78. 85

It will be understood that while the parts are positioned as illustrated in Fig. 3 the machine may be run through its cycle any desired number of times without the feeding of tacks to the tack pockets. It will be evident, however, that in the first cycle of the machine under these conditions tacks fed to the tack pockets at the end of the previous cycle will be discharged, and that before resuming normal use of the machine on a shoe it will be necessary to run the machine through at least one cycle with the illustrated controlling mechanism in its normal position, in order to supply the tack pockets with tacks to be used in the shoe. 100

While the invention is illustrated as applied to a machine which utilizes tacks, it will be understood that it is not limited to the use of fastenings of that particular kind; and it will also be understood that the invention is not limited as to the number of fastenings driven in the cycle of the machine. 105

Having described the invention, what I claim as new and desire to secure by Letters Patent of the United States is:

1. In a machine of the class described, the combination with means for driving a fastening in a cycle of operations of the machine, and means for feeding a fastening to the driv- 110

ing means in the course of the cycle, of mechanism constructed and arranged for use at the will of the operator either to prevent the feed of any fastening and also the operation of the driving means during the cycle or to prevent such feed without preventing the operation of the driving means.

2. In a machine of the class described, the combination with means for driving a fastening in a cycle of operations of the machine, and means for feeding a fastening to the driving means in the course of the cycle, of a device movable at the will of the operator either into position to prevent the feed of any fastening and also the operation of the driving means during the cycle or into position to prevent such feed without preventing the operation of the driving means.

3. In a machine of the class described, the combination with a member movable to drive a fastening in a cycle of operations of the machine, and a separator movable to feed a fastening in the course of the cycle, of mechanism constructed and arranged for use either to prevent the normal movements of said member and separator during the cycle or to prevent the normal movement of the separator without interfering with the movement of said member.

30 4. In a machine of the class described, the combination with a member for driving a fastening in a cycle of operations of the machine, and a separator for feeding a fastening in the course of the cycle, of a device movable either into position to prevent the normal operation of said member and of the separator during the cycle or into position to prevent the normal operation of the separator only.

40 5. In a machine of the class described, the combination with spring-operated means for driving a gang of fastenings in a cycle of operations of the machine, a separator for feeding fastenings in the course of the cycle, and an oscillatory hopper arranged for use to control said separator, of means movable either into position to obstruct the movements of said driving means and hopper during the cycle or into position to obstruct the movement of the hopper only.

60 6. In a machine of the class described, the combination with spring-operated drivers for driving a gang of fastenings in a cycle of operations of the machine, a separator for feeding fastenings in the course of the cycle, and an oscillatory hopper arranged for use to control said separator, of a driver-controlling member movable at the will of the operator either into a position to prevent the normal operation of the drivers during the cycle or into a position to permit such operation, and another member connected to said driver-controlling member and arranged to prevent the normal movements of the hopper and therefore the feeding of fastenings

by the separator when the driver-controlling member is in either of said position, said members being movable to other positions such as to permit the normal operations of both the hopper and the drivers.

70 In testimony whereof I have signed my name to this specification.

JACOB C. JORGENSEN.
